LOUIS JUDELSON

BY
Maurice Finckstein
ATTORNEY

UNITED STATES PATENT OFFICE.

LOUIS JUDELSON, OF NEW YORK, N. Y.

CLOTHES WRINGER.

Application filed April 22, 1922. Serial No. 555,947.

To all whom it may concern:

Be it known that LOUIS JUDELSON, citizen of the United States, residing at the city of New York, in the county of Bronx and State 5 of New York, has invented certain new and useful Improvements in Clothes Wringers, of which the following is a specification.

This invention relates to clothes wringers. One object thereof is to provide in a device 10 of the character described practical means for safeguarding the operator from injury.

Another object of this invention is to provide in a device of the character described, practical means for protecting the machine 15 from injury when articles of greater bulk than the machine is designed to carry are inserted therein.

A still further object is to provide a device of the character described which shall 20 be efficient in operation to a high degree, of simple construction and comparatively cheap to manufacture.

Other objects of this invention will in 25 part be obvious and in part hereinafter pointed out.

The invention accordingly consists in the features of construction, combinations of elements and arrangement of parts which will be exemplified in the construction hereinafter described, and of which the scope of 30 application will be indicated in the following claims.

In the accompanying drawings, in which is shown one of various possible illustrative 35 embodiments of this invention,

Fig. 1 is a front elevation of an embodiment of my invention;

Fig. 2 is a plan view thereof;

Fig. 3 is a partial rear elevation of the 40 upper portion of the device showing the resetting hand lever in position for maintaining the wringer rolls in operative relation to each other;

Fig. 4 is a detailed sectional view taken 45 along line 4—4 of Fig. 1;

Fig. 5 is a partial view similar to Fig. 3 showing the reset hand lever in raised vertical position and the wringer rolls in separated position;

50 Referring in detail to the drawing, 10 is the machine frame consisting of the upright standards 11, 11' secured in the base 12 and a cross member 13 normally secured at their upper ends. The standards 11, 11' carry

the gear casings 14, 14' in which are housed 55 the pairs of gears 15, 15' and 16, 16'. The lower gears 15, 16 are supported on the horizontal shaft 17 which in turn is journaled in bearings 18, 18' in the standards 11, 11'. The shaft 17 extends at one end 60 17' thereof into the transmission box 19 supported on the base 12, by any suitable means such as the bolts 19'. Supported above shaft 17 is the upper shaft 20 journaled in a pair of vertically movable bearing blocks 21, 21' 65 mounted in the standards 11, 11'. The shafts 17 and 20 carry the usual wringer rolls 22, 23. Mounted to the front and rear of the lower roll 22 is a pair of guide rolls 24, 24' supported in brackets 25, 25'. The bearing blocks 21, 21' are recessed as at 26, 26' to provide seats for the lower ends of the tension springs 27, 27'. The upper ends 28, 28' of these springs are disposed in similar inverted recessed portions 29, 29' formed 70 in the presser blocks 30, 30' at the ends of the tension bar or cross-member 31 and preferably formed integral therewith. For tensioning the rolls 22, 23 pressure is applied to the tension bar 31 by means of the hand wheel 32 having a threaded shank 32' extending through a central opening 33 of the cross-member 13. 80

Power means is provided for rotating the rolls 22, 23 and for reversing the direction 85 of rotation thereof when desired. To this end a reversing power drive is provided for one of the shafts such as the lower shaft 17 comprising a pair of beveled gears 34, 34' mounted in opposed relation to each other 90 and in operative relation to the gear 35 at right angles thereto. The latter is driven by the power shaft 39 operated by any prime mover such as the electric motor 40 (not shown). 95

A clutch 36 is provided for throwing either one of the gears 34, 34' into mesh with the driving gear 35. This clutch is operated by a link member 37 pivoted to a horizontal arm 38 extending across the wringer beneath the rollers. This arm 38 is provided with an operating handle 38' and notches 38'', 38''', whereby the arm may be held in adjusted position, as will be readily understood. As will be clear from the drawing, when link member 37 is in position A, bevel gear 34' is in mesh and shaft 17 will be driven in one direction, and when 100 105

the link is in the position shown at C, the bevel gear 34 will be in mesh and the shaft driven in the opposite direction. When the link is in the neutral position B, the shaft is 5 at rest.

The means for separating the upper wringer roll 22 from the lower roll 23 will now be described. Straddling each end 13^a, 13^b of the cross member 13 are the keepers 10 42, 42' preferably inverted U-shaped as shown in Fig. 4. The keepers 42, 42' extend downwardly over the cross member 13 and are pivotally secured as at 43, 43' to the standards 11, 11'. A hand lever 44 is 15 provided at the rear of the machine pivoted by means of a pin 44^c to the cross member 13. This hand lever carries a pair of link arms 45, 45' for connecting the keepers 42, 42' respectively thereto. The arm 45 is piv- 20 otally connected at one end as at 44^a to the lower end of the lever 44, and is pivoted at the other end as at 46 to the keeper 42. The arm 45' is pivotally secured to the lever 44 above the arm 45 as at 44^b and at the 25 other end to the keeper 42' as at 47.

The operation of the safety device for the separation of the rolls will now be clear. When the lever 44 is in inclined closed position (Figs. 1 and 3), the keepers 42, 42' 30 straddle the cross member 13, thus holding the tension bar 31 down with the presser blocks 30, 30' thereof compressing the springs 27, 27'. The wringer rolls are then in operative position and under proper ten- 35 sion as previously adjusted by the hand wheel. If the operator should get a hand caught between the rolls, he quickly strikes the hand lever 44 throwing it into open vertical position shown in Fig. 5. The link 40 arms 45, 45' connected to the hand lever will then push outward on the keepers 42, 42' causing them to rotate out of holding position, thus releasing the presser bar 31 and cross member 13. The bearing blocks 21, 45 21' will then move upward together with the shaft 20 and the roll 23, thus quickly separate the rolls and free the hand. The rolls may then be re-set for operation by 50 turning the hand wheel 32 to release the tension setting, swinging the hand lever 44 down to simultaneously restore both keepers to their effective position, and then readjusting the tension applied to the rolls by turning said wheel 32 as will be readily understood.

It will thus be seen that there is provided apparatus in which the several objects of this invention are achieved and which is

well adapted to meet the conditions of practical use.

As various possible embodiments might be made of the above invention and as various changes might be made in the embodiment above set forth, it is to be understood that all matter herein set forth or shown in the accompanying drawings is to be interpreted as illustrative and not in a limiting sense.

Having thus described my invention, I claim as new and desire to secure by Let- 70 ters Patent:—

1. A wringer including a frame having supporting standards, a shaft journalled in said standards and carrying a wringing roller, a second shaft arranged above the first shaft carrying a wringing roller, springs bearing on said second shaft, a tension bar extending between said standards and having its ends bearing on said springs, an upper cross-bar arranged between the standards and located above the tension bar, inverted U-shaped members pivotally connected to the upper ends of said standards and normally engaging the upper surface of the cross-bar, an operating handle pivotally connected intermediate its ends to said cross-bar, a link pivotally connected to one end of said operating handle and having one of its ends pivotally connected to one of the U-shaped members, a second link having one of its ends pivotally connected to one of the U-shaped members, the other end of the second link being pivotally connected to the handle.

2. A wringer including a frame having supporting standards, a shaft journalled in said standards and carrying a wringing roller, a second shaft arranged above the first shaft carrying a wringing roller, springs bearing on said second shaft, a tension bar extending between said standards and having its end bearing on said springs, an upper cross-bar arranged between the standards and located above the tension bar, releasable means pivotally mounted on relatively stationary parts of the wringer for securing the cross bar in fixed position with respect to said parts, means positioned between the cross bar and the tension bar for adjusting the effective compression of the springs, and a single means for simultaneously releasing and re-setting said first mentioned means.

In testimony whereof I affix my signature.

LOUIS JUDELSON.
